(57) **CLAIM**

I claim the ornamental design for a liquid crystal video projector, as shown and described.

DESCRIPTION

FIG. 1 is a top perspective view of a liquid crystal video projector of the present invention;
 FIG. 2 is a front view thereof;
 FIG. 3 is a rear view thereof;
 FIG. 4 is a first side view thereof;
 FIG. 5 is a second side view thereof;
 FIG. 6 is a top view thereof; and,
 FIG. 7 is a bottom view thereof.
